UNITED STATES PATENT OFFICE.

HERBERT D. CLAYTON, OF HILL CITY, KANSAS.

MERRY-GO-ROUND.

Application filed December 11, 1924. Serial No. 755,240.

My invention relates to a merry-go-round or circle swing for children and particularly to a merry-go-round or swing which is turned by the children either by engaging 5 the ground with their feet to turn the merry-go-round or by grasping arms of the merry-go-round and running about the axis thereof.

The general object of my invention is to 10 provide a merry-go-round or swing of the indicated type improved in various particulars especially with respect to the seating assemblage whereby the maximum seating capacity is provided, strength in the 15 merry-go-round structure is promoted, as well as to provide a merry-go-round characterized by the convenience and safety with which it may be operated.

The nature of my invention and its distinguishing features and advantages will 20 clearly appear as the description proceeds.

Reference is to be had to the accompanying drawings forming a part of this specification, it being understood that the drawings 25 are merely illustrative of one example of the invention.

Figure 1 is a perspective view of a merry-go-round embodying my invention;

Figure 2 is a plan view showing on an 30 enlarged scale a seating arrangement;

Figure 3 is a front elevation of the parts shown in Figure 2.

In carrying out my invention in accordance with the illustrated example, a mast 10 is erected and extending from the mast adjacent the base thereof are inclined arms 11. Also hanger arms 12 are provided extending from a suitable fitting 13 on the mast 10 near the top and downwardly in divergent 40 relation. The upwardly and outwardly disposed arms 11 and the downwardly and outwardly disposed arms 12 serve to carry a seat assemblage. Said seat assemblage comprises seats 14 in one plane and alternating seats 15 in a lower plane. Thus the seats 14, 15 alternately higher and lower are disposed about the merry-go-round in continuous series, each seat running at right angles to a radial line struck from the mast 10. 50 Thus, the connection between the arms 11, 12 and the adjacent ends of adjacent seats 14, 15 is effected by the use of spacing blocks 16 between the seats 14, 15 at the ends thereof and vertical bolts 17 having nuts 18. 55 The bolts 17 pass through feet 19 on the lower ends of the arms 12, through the spac-

ing blocks 16, and through feet 20 on the upper ends of the upwardly extending arms 11 and therefore the tightening up of the nuts 18 on bolts 17 serves to secure in an effective and simple manner the ends of adjacent seats to one another and to the arms 11 and 12.

The occupants of the seats 14, 15 face outwardly instead of in the direction of turning 65 of the merry-go-round and the children in that way may cause the merry-go-round to turn by those seated pressing one foot against the ground and also the construction permits of children standing on the ground 70 inside of the seats and taking hold of the arms 11 and in that way running about with the turning of the structure, it being well recognized that children in playing with merry-go-rounds enjoy the running equally 75 with the riding. The depressed seats 15 have backs 21, two of such backs being shown and the others being omitted in the interest of clearness. Said seat backs 21 are, like the seats 14, 15, disposed at right 80 angles to a radial line instead of on a radial line or approximately so as in the common form of merry-go-rounds. Some advantages 85 of the construction described in addition to those referred to are that small children 90 may be properly accommodated on the lower seats and larger children on the higher seats; and the form and arrangement of the parts enables the structure to be cheaply constructed and assembled with facility. 90

I would state in conclusion that while the illustrated example constitutes a practical embodiment of my invention, I do not limit myself strictly to the exact details herein illustrated, since, manifestly, the same can 95 be considerably varied without departure from the spirit of the invention as defined in the appended claims.

Having thus described my invention, I claim:—

1. A merry-go-round of the class described, including a mast, a series of arms near the foot of the mast and extending outwardly and upwardly, a series of arms having support at their upper ends on the mast 105 and extending downwardly and outwardly to points adjacent the terminals of the first-mentioned arms, a plurality of seats disposed in a series about the merry-go-round at the outer ends of the arms, alternate seats 110 being depressed in a plane below the adjacent seats, the seats of said series over-

lapping at adjacent ends and spaced, means securing the overlapped ends of the seats to both series of arms at the outer ends thereof.

2. A merry-go-round of the class described including a mast, a series of seats disposed about the mast distant therefrom and overlapping one another, alternate seats being at a higher level than adjacent seats; together with arms extending from

the mast adjacent the base thereof to said 10 seats and other arms extending from the mast near the top to said seats, both series of arms being turnably mounted at their inner ends, and one arm of each of said series being connected with the overlapped 15 ends of two adjacent seats.

HERBERT D. CLAYTON.
